[57] CLAIM

The ornamental design for a toilet brush holder, as shown and described.

DESCRIPTION

FIG. 1 is a top left front perspective view of a toilet brush holder showing our new design;

FIG. 2 is a front elevational view thereof;

FIG. 3 is a top plan view thereof;

FIG. 4 is a left side elevational view thereof; the right side elevational view being a mirror image;

FIG. 5 is a rear elevational view thereof; and,

FIG. 6 is a bottom plan view thereof.

The surface pattern, which is fragmentally shown in FIGS. 1 and 2, is understood to repeat uniformly and continuously across the entire indicated surfaces.
